UNITED STATES PATENT OFFICE.

ELLIS L. HALE AND HARRY GLEN COULSON, OF WALLACE, IDAHO, ASSIGNORS TO COEUR D'ALENE HARDWARE & FOUNDRY CO., OF WALLACE, IDAHO.

RAILWAY DUMP CAR.

Application filed August 28, 1922. Serial No. 584,606.

To all whom it may concern:

Be it known that we, ELLIS L. HALE and HARRY G. COULSON, citizens of the United States, residing at Wallace, in the county of Shoshone and State of Idaho, have invented certain new and useful Improvements in Railway Dump Cars, of which the following is a specification.

Our invention relates to certain new and useful improvements in railway cars used for hauling ore, coal, rock, earth, or the like, and it is intended to facilitate the tipping of the car body, when dumping its contents, and the restoring of the body to its normal position; also to provide means to automatically open and close the car door.

The invention further has for its object to provide a dump car with a body arranged to be tilted toward one side or end which is provided with a hinged door; an object of the invention being to provide a toggle lever locking mechanism for opening, closing and locking the hinged door accordingly as the body is tilted more or less and also to provide a single operating lever for effecting the tilting of the body and the simultaneous operation of the door.

Again the invention has for its object to provide a dump car of the character stated of a simple, strong and inexpensive nature by the use of which it is quite possible for the operator to distribute track ballast as a car moves slowly along by holding the operating lever in such position that the body is partially tipped and the door opened slightly so that the material gradually spills out; the amount of track ballast thus deposited being regulated to a nicety by holding the dumping or operating lever in a position to give the desired amount.

The invention further resides in those novel features of construction, combination and arrangement of parts, all of which will be first fully described, then be specifically pointed out in the appended claims, reference being had to the accompanying drawings, in which:

Figure 1 is a perspective view of a dump car embodying the invention, the view being taken from the dump lever side at one end of the car.

Figure 2 is a view similar to Figure 1 taken from the other side of the car.

Figure 3 is a perspective view similar to Figure 1 with the car body completely tipped and the door completely opened.

Figure 4 is a perspective view similar to Figure 2 with the body tilted and door opened to about four-fifths of the maximum distance.

Figure 5 is an end elevation showing the car in the normal position in full lines.

Figure 6 is a detail end view illustrating the position of the door operating toggle lock levers in the open position in full lines.

Figure 7 is an enlarged detail elevation of a portion of the dumping or operating lever and the link connection with the car body.

Figure 8 is a detail perspective view of the pivot portion of the dumping lever.

Figure 9 is a detail perspective view of the link used to connect the dumping lever with the car body.

Figure 10 is a detail perspective view of the pivot bracket carried by the car body, to which one element of the toggle levers connects.

Figure 11 is a detail sectional view showing the toggle levers connected to the bracket element and the bracket element connected to the car body.

In the drawings in which like numerals of reference indicate like parts in all of the figures, the frame 1 (which may be made of wood or metal) is carried upon suitable car wheels 2 and axles 3 and constitutes a truck. Bolted to the frame 1 are three body supports 4, 4 and 5, each of which is provided with an inclined portion 4^a, 4^a and 5^a, respectively, to act as a stop or rest for the car body in the fully tilted position. The car body 13 is pivotally attached to the supports (I-beams being shown in the embodiment of the invention illustrated) by means of angles 6, bolts 29 and pivot blocks 7.

Attached to the middle support 5 by bolts 9 is a dump lever pivot 8. Pivoted upon the dump lever pivot 8 is the offset bell crank portion 11 of the dumping lever 10. An I-block 12 is attached to the body 13 and is connected to the lower arm of the bell crank 11 by means of a link 14. The lever is held in normal position by the keeper link 16 which is kept in place by the D-clip 15 riveted to the body. To tip the car body, the lever 10 is loosened from the link 16 and

turned about its pivot 8 through an angle of about one hundred and thirty degrees until it strikes the stop piece 17. The body is restored by bringing the lever 10 back up to 5 the first position.

The door 18 is hinged by means of a rod 19 to the upper corner of the body 13 and has attached, at its lower edge, a trunnion 20 at each end. Secured at each end of the 10 body 13 is a pivot post 21, upon which is mounted one end of a pair of horizontal levers 22 (constituting one element of a toggle lever system), the inner end of the pair of levers 22 is connected to the inner end of a 15 bent link 23 which has its outer end pivoted to the trunnion 20. The frame 1 has mounted upon it, at each end, a link bracket 24 which is provided with a pivot pin 25. The pivot pin 25 is connected by an upright link 26 to a pin 27 in the pair of horizontal 20 levers 22. The link 23 is bent to pass over the pivot post 21 and the upper end of the upright link 26, so that in the normal position the pin 28 lies below a center line 25 drawn through trunnion 20 and pivot post 21, thus providing a toggle lock for the door 18. It should be understood that the toggle link lever set is duplicated on the end of the car opposite to that shown in Figures 1 to 4, 30 inclusive, of the drawings.

The action of this automatic door mechanism is as follows: When the car body is being tipped, the pivot post 21 moves downward on an arc about the bolt 29 as a center. The pin 27 acts as a fulcrum for the 35 lever 22, and at the same time swings on a downward arc about the pin 25 as a center. Because of the relative locations and travel of the pivot post 21 and fulcrum pin 27, the 40 end of the lever 22 and the pin 28 describes an arc about post 21 as a center. This movement of pin 28 is imparted to trunnion 20 by the link 23 and serves to swing the door 18 outward about the rod 19 as a center. The lever 22 and the links 26 and 23 act 45 in the reverse order to close the door 18 when the body 13 is restored to its normal position by the action of the lever 10. When the body is nearing its normal position, the 50 link 23 and lever 22 have a powerful toggle action which brings the door 18 tightly up against the body 13.

The chief advantage of the dumping lever is that cars of any size may be easily dumped 55 by one man. It also makes possible the use of larger cars, which could not before be dumped by the old direct hand method of tipping. The main advantage of the door opening and closing mechanism is that it is 60 entirely automatic; no additional hand levers or latches of any kind are necessary and furthermore the door is more securely held than by most other devices. An advantage secured by the combination of dumping 65 lever and automatic door mechanism is that

the operator is able to distribute track ballast as a car moves slowly along by holding the dumping lever in such a position that the body is partially tipped and the door 70 opened slightly so that material gradually spills out. The amount of track ballast thus deposited may be regulated to a nicety by holding the dumping lever in a position to give the desired amount.

Suitable baffles or sheds 30 may be provided on the car body above the toggle lever mechanism to shunt any spilled rock or material away from the levers and thus avoid 75 débris falling on the levers, which might clog their action.

While we have illustrated our invention as a metallic dump car, it is to be understood that the material employed in constructing the body and truck may be any 80 that is suitable for the purpose.

From the foregoing description, taken in connection with the accompanying drawings, it is thought the complete construction, operation and advantages of our invention 85 will be readily understood by those skilled in the art to which it appertains.

What we claim is:

1. In a dump car, a truck, an end pair of body supports and a middle body support mounted on said truck, a body pivoted to 95 said end supports, a dumping lever pivoted to said middle support, a link connecting said lever to said body and a link on said body detachably engaging said lever to hold it.

2. In a dump car, a truck, an end pair of body supports and a middle body support mounted on said truck, a body pivoted to 100 said end supports, a dumping lever pivoted to said middle support, a link connecting said lever to said body, a link on said body detachably engaging said lever to hold it, a gate hinged at one end to said body, toggle levers connecting the free end of said gate with said body and lying along the ends of the same, an upright link pivoted to said truck and to an element of said toggle levers to operate the same as the body is tilted.

3. In a dump car, a truck, an end pair of body supports and a middle body support mounted on said truck, a body pivoted to 110 said end supports, a dumping lever pivoted to said middle support, a link connecting said lever to said body, a link on said body detachably engaging said lever to hold it, a gate hinged at one edge to said body, sets 115 of levers connecting the free end of said gate with said body, an upright link pivoted to the truck and to an element of said sets of levers to operate the same as the body is tilted.

4. In a dump car, a truck, a car body pivoted on said truck, a door hinged to the top of said body on an axis parallel to that 120 of the body pivot, a dumping lever pivoted 125

to said truck on an axis at right angles to the pivotal axis of the body, operating connections between said lever and body, and toggle lever and link devices connecting 5 said door, said body and said truck for operating said door according to the inclination of said body.

5. In a dump car, a truck, a car body pivoted on said truck, a door hinged to the 10 top of said body on an axis parallel to that of the body pivot, a dumping lever pivoted to said truck on an axis at right angles to the pivotal axis of the body, a link connection between said lever and said body, toggle levers connecting said door and said body and a link connecting said toggle levers with said truck whereby as said dumping lever is moved and said body tilted, said door will be moved proportionately 15 thereto.

6. In a dump car, a truck, a car body pivoted on said truck, a door hinged to the 20 top of said body on an axis parallel to that of the body pivot, a dumping lever pivoted to said truck on an axis at right angles to the pivotal axis of the body, a link connection between said lever and said body, toggle lever elements pivoted at one end to said door, toggle lever elements pivoted at 25 one end to said body, said toggle lever elements being pivoted together, an upright link mounted at one end on said truck and

pivoted at the other end to one of said toggle lever elements.

7. In a dump car, a truck, a car body pivoted on said truck, a door hinged to the 30 top of said body on an axis parallel to that of the body pivot, a dumping lever pivoted to said truck on an axis at right angles to the pivotal axis of the body, a link connection between said lever and said body, toggle lever elements pivoted at one end to said door, toggle lever elements pivoted at one end to said body, said toggle lever elements being pivoted together, an upright link 35 mounted at one end on said truck and pivoted at the other end to one of said toggle lever elements, said first mentioned toggle lever elements being bent to lie over the pivot of said second mentioned toggle lever 40 elements.

8. In a dump car, a truck, a plurality of body supports having horizontal and inclined faces to sustain the car body horizontally and tilted, a car body pivoted to 45 said supports, a dumping lever pivotally mounted on said truck on an axis at right angles to the pivotal axis of the body, a link connecting said dumping lever to said body, and means for holding said dumping lever 50 in the normal position.

ELLIS L. HALE.
HARRY GLEN COULSON.
